(57) **CLAIM**

The ornamental design for a camera mounting plate with deployable attachment point, as shown and described.

DESCRIPTION

FIG. 1 is an isometric view of a new design for a camera mounting plate with deployable attachment point;

FIG. 2 is a top plan view thereof;

FIG. 3 is a bottom view thereof;

FIG. 4 is a rear side view thereof;

FIG. 5 is a front side view thereof;

FIG. 6 is a right side view thereof;

FIG. 7 is a left side view thereof;

FIG. 8 is an isometric view thereof, with the attachment point deployed;

FIG. 9 is a bottom plan view thereof, with the attachment point deployed;

FIG. 10 is a rear view thereof, with the attachment point deployed;

FIG. 11 is a left front side view thereof, with the attachment point deployed;

FIG. 12 is a right side view thereof, with the attachment point deployed; and,

FIG. 13 is a left side view thereof, with the attachment point deployed.

The broken lines shown depict portions of the camera mounting plate that form no part of the claimed design.
